UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A LADY'S BASQUE.

SPECIFICATION forming part of Design No. 15,581, dated November 25, 1884.

Application filed September 12, 1884. Term of patent 3½ years.

To all whom it may concern:

Be it known that I, LOUISE TULLY, of the city, county, and State of New York, have invented and produced a new and original Design for a Pattern of a Lady's Basque, (numbered 9,424;) and I do hereby declare that the engraved prints accompanying this specification convey to any one accustomed to using paper patterns a clear understanding of how a garment made up by the pattern will appear.

The design shows closely-fitted fronts exhibiting two graduated pointed straps across the closing, and having their front edges reversed above the closing in lapels and below the closing in revers, to display a closely-fit-

ted pointed rest having a fastening all the way down, a closely-fitted back displaying an underfolded double box-plait at the lower end of its middle seam, coat-sleeves exhibiting a gathering and a high roll at the shoulder, a standing collar, and a rolling collar flaring from the tops of the lapels at its front ends.

What I claim as my invention, and desire to secure by Letters Patent, is—

The design for a lady's basque, as shown in the engraved prints accompanying this specification.

LOUISE TULLY.
